ABSTRACT OF THE DISCLOSURE

A maintenance apparatus and motor vehicle for transporting liquid and for processing said liquid into snow for use in replenishing the snow covering for bare spots or worn areas found on a ski slope or other winter sports area, said motor vehicle having a track type chassis with a driver's cab mounted thereon, said maintenance apparatus being mounted on said vehicle chassis and comprising power means for compressor and pump means and electric generator, electric heating means for the prevention of freezing of the snow making liquid prior to ejection; electric control means for operation of said apparatus; an insulated storage tank for liquid used in making snow; hose means having separate channels therein for air and said liquid; the said hose having one end attached to said apparatus and the other end attached to an aspirating snow gun spray nozzle, said nozzle having mounted thereon a mixing chamber and flow control switches for air and liquid, said hose being of sufficient length to permit the operator of the nozzle to reach all parts of the repair area.

BACKGROUND

Field of invention

This invention relates to the art of making snow for use on winter sports areas where snow is required, such as a ski slope. The snow is made through the use of apparatus for simulating the action of nature in producing natural snow when the temperature is below freezing and natural snow is not forthcoming.

Description of prior art

The prior art apparatus used in the snow making art of which applicant is familiar is best shown in the Pierce Pat. No. 2,676,471 for making and distributing snow on a ski slope where the apparatus is located near a water source and consists of a water pump and an air compressor. Separate pipe lines are connected to said pump and compressor and are laid on the slope with valve takeoffs at various points on said slope for connection to a manifold type distributor with nozzle outlets for the snow forming spray. The Pierce portable trailer unit uses substantially the same apparatus having a water pump and an air compressor mounted on the top of a water tank with distributing features that are somewhat the same as in the slope apparatus.

SUMMARY

In contrast with the prior art in the maintenance apparatus and vehicle field used in replenishing snow for the repair of ski slopes and other winter sports, the present invention avoids the disadvantages found in such art in the following respects, among others: The maintenance apparatus and vehicle combination of the present invention provides advantage of a complete self-contained unit for making and distributing snow at the place where snow is required for a satisfactory use of the winter sports area. Another advantage is that the problem of freezing is removed from the snow making liquid and the con-

2

densate in the air lines prior to the ejection thereof at the nozzle. Another advantage is that the nozzle has electric control switches mounted thereon for control of the liquid and air during operation of the apparatus and nozzle. Still another advantage is that the apparatus is efficient in use of apparatus and the amount of liquid required for operation.

Other advantages more or less ancillary to the foregoing will appear in the following description and the accompanying drawings of the invention.

THE DRAWINGS

The invention is illustrated in the drawings in which conventional parts are omitted or merely indicated to clarify the specification.

In the drawings:

FIG. 1 is a perspective view of the vehicle with the apparatus of the invention mounted thereon;

FIG. 2 is a perspective view of the apparatus within its housing and the arrangement of the various parts; and

FIG. 3 is an enlarged detail view of a part of the hose lines and shown partly in section.

THE PREFERRED EMBODIMENTS

The maintenance apparatus and vehicle combination and the machine parts associated therewith is illustrated in FIGS. 1, 2 and 3 of the drawing. The various important units of the apparatus are shown in FIG. 2 after being assembled and mounted in a housing frame shown as a line drawing to make more clear the location of the said units. FIG. 1 shows the apparatus associated with the said housing mounted on the chassis of a track type vehicle particularly adapted for snow or ice covered terrain and shows the liquid storage tank of the combination mounted on said vehicle chassis between the vehicle cab and said apparatus housing. FIG. 3 shows in detail the unique hose assembly used to carry the liquid and air to the mixing and ejecting nozzle unit.

It will be seen that the combination of the invention and component parts thereof comprise the following major units: a track type motor vehicle A, a storage tank B, the maintenance apparatus and its housing C and a hose and distribution system D.

The said track type motor vehicle A includes a chassis 10, a cab 11 mounted on said chassis 10 and caterpillar type endless belt treads 12. Also included therein and mounted on said chassis 10 but not shown in the drawing area: a motor vehicle type engine and accessories therefor, a transmission and drive unit connected to said engine and drive wheels for moving said caterpillar treads 12, a steering system and an electrical system.

The said storage tank B has a tank section 15 preferably insulated. The tank section 15 has an opening 16 in its top wall with a tubular filter neck 17 affixed to the periphery of said opening 16 and containing filters for filtering the liquid solution as it is poured into the tank section 15. A storage tank having a capacity of approximately 100 gallons has been found to be satisfactory. Preferably the said storage tank 15 has a bottom wall 55 slightly conical in a downward direction and having a pipe connection opening in the apex of said wall for better drainage on slope side operation.

The said maintenance apparatus and housing C may be assembled in a housing 20 preferably of metal panel sections with support frames (not shown) for mounting the various parts of said apparatus therein and having one side panel section 21 serving as an instrument panel for such apparatus.

Mounted within said housing 20 are an engine 22 preferably of the propane fuel type, a compressor 23 powered by said engine 22, a compressed air storage tank 24 having a pipe (not shown) connected to said compressor

23, a pump 25 powered by said engine 22 and having a pipe on the suction side thereof connected to said pipe connection of the liquid storage tank 15 and an electric generator 26 powered by said engine and a 12 volt DC battery 26A.

Mounted on said side panel 21 outer wall are a fuel tank 27 having a pipe connected to the carburetor (not shown) of said engine, a duplex gauge 28, a voltmeter 29, an air pipe coupling 30 having a pipe (not shown) connected to said air tank 24, a liquid pipe coupling 31 having a pipe (not shown) connected to the pressure side of said pump 25, an electrical receptacle 32 having wires connected to said generator 26, an electrical receptacle 33 having wires connected to said 12 volt DC battery 26A and to the magnetic clutch of the pump 25 and to a solenoid type valve in the liquid pipe line connected to said pump 25, and an electrical receptacle 34 having wires connected to said 12 volt DC battery 26A and to a solenoid type valve in the compressed air pipe line from the air tank 24.

The hose and distribution system D includes a hose 40 connecting said liquid storage tank 15 and said pump 25, a distribution hose 41 carrying air and liquid and an aspirating type snowgun nozzle 42 having a liquid and air mixing chamber 43 affixed to the end 44 of the hose 41.

The said distribution hose 41 has included therein a liquid hose 45 and an air hose 46 in separate channels, an electrical heating tape 47 spirally wrapped around said liquid hose 40 and 45 and air hose 46 and connected to said receptacle 32, an electrical liquid control circuit 48 and an electrical air control circuit 49, said electrical liquid control circuits 48 and 49 being connected to a button control switch 50 mounted on said nozzle 42 and being connected to the electrical receptacles 33 and 34 on said panel to acuate a clutch solenoid attached to said pump 25 and to acuate a solenoid valve in the air line from the air tank 24.

The said liquid hose 45 is connected to said liquid pipe coupling 31 and to said nozzle 42 adjacent said mixing chamber 43 and the said air hose 46 is connected to said air pipe coupling 30 and to said nozzle 42 adjacent said mixing chamber 43.

A standby electrical receptacle may be added to the said electrical heating circuit for connection to an external source such as a line current for use when the engine 22 is not in operation to prevent freezing of the liquid in the hose lines 40 and 41.

It has been found that a water supply devoid of minerals is best suited for use in making snow and that the addition of a chemical foaming agent to the water that will cause the water to foam upon its ejection from the nozzle into the ambient air will give superior results.

A protein chemical foaming agent of the type that will not injure the vegetation in the area has been found to be satisfactory for use. One-half to one percent of the volume of water in the tank 15 is a sufficient amount of chemical to be added for satisfactory results.

The foregoing description of the maintenance apparatus and vehicle shows that it is a complete and self-contained unit that may be moved to any area of a ski slope or winter sports area where snow is required and that snow would be made and distributed as desired by the operation of the nozzle 42 in air temperatures that range from approximately 30° F. to at least 30° F. below zero.

In operation the liquid solution for making snow is first placed in the tank 15 and the engine 22 is started to operate the air compressor 23 to create an air pressure of approximately 110 p.s.i. in the air tank 24 for use in the operation of the apparatus.

The track type vehicle with the maintenance apparatus mounted thereon is then moved under its own power to a position adjacent the area to be covered with snow. The operator, after leaving the cab 11, unlimbers from the vehicle so much of the distribution hose 41 as seems desirable and with the nozzle 42 pointed toward the area

to be snow covered closes the button switch 50 adjacent the rear of the nozzle 42. The closing of said switch 50 actuates the solenoid in said circuit 48 which opens the valve in the solution pipeline between the pump 25 and tank 15 and also closes the pump clutch between the engine 22 and the pump 25 to start the operation of said pump. The pump as stated draws liquid solution from the tank 15 on its suction side and forces the liquid solution into the hose 41 under pressure on its discharge side. The pressure of the liquid solution in the hose 41 should be approximately 110 p.s.i. to equal the pressure in the air tank 24. The closing of the button switch 50 also actuates the solenoid which opens the valve in the air pipeline in said circuit 49.

It will be seen that when the button switch 50 has been closed the pump 25 will start operating and forcing the liquid under pressure through the hose 41 and the compressed air from the air tank 24 will begin flowing through the hose 41. The liquid and air will flow into the mixing chamber 43 where such liquid and air will be mixed. The mixed liquid and air will then pass into the aspirating nozzle 42 where the mixture will receive additional air having a temperature below freezing. Thus the said mixture as it is ejected from the nozzle 42 will have the proper temperature below freezing to form snow without delay.

Although the foregoing description is necessarily of detailed character, in order that the invention may be completely set forth, it is to be understood that the specific terminology is not intended to be restrictive or confining, and that various arrangements of parts and modifications of detail may be resorted to without departing from the scope or spirit of the invention as herein claimed.

What is claimed is:

1. A maintenance apparatus and vehicle therefor for making snow comprising:

- (a) a motor vehicle having a track type chassis, a driver's cab mounted thereon,
- (b) an insulated storage tank for liquid used in making snow, removably mounted on said chassis,
- (c) a maintenance apparatus housing removably mounted on said chassis adjacent said storage tank,
- (d) the said maintenance apparatus mounted in said housing comprising: an internal combustion engine and control means therefor, an air compressor and a liquid solution pump and an electric generator powered by said engine, a 12 volt DC battery, an air tank having an air pipeline connected to said air compressor, a liquid solution carrying hose pipeline with temperature control heating means therefor connected to said pump and said storage tank, an electric circuit control means for said pump and liquid solution hose pipeline and an electric circuit control means for said air pipeline connected to said battery and an electric circuit heating means electrically connected to said generator,
- (e) a side wall of said housing serving as an instrument panel for said apparatus mounted in said housing,
- (f) said instrument panel including an engine fuel tank with a fuel pipeline connection to said engine, an air and liquid duplex pressure gauge, a voltmeter, an electric circuit control receptacle for said air pipeline, an air pipeline coupling and a liquid pipeline coupling, the said instruments having connections to the respective units of apparatus associated therewith,
- (g) a dual pipeline distribution hose having separate channels for said liquid solution and air under pressure, temperature control electric heating means for said distribution hose, said hose channels connected at one end to said liquid solution and air couplings on said instrument panel, an aspirating type snow gun nozzle having a liquid and air mixing chamber adjacent its base, separate connections in said nozzle

base for said liquid solution and air channels of said distribution hose, and

(h) said dual pipeline distribution hose carrying said electric circuit control means for said liquid solution and air pipelines to said nozzle and a control center on said nozzle for said electric control means for said liquid solution and air pipelines.

2. The maintenance apparatus defined in claim 1 in which the temperature control electrical heating means for said hose pipeline connecting said storage tank and pump and said dual pipeline distribution hose is an electrical heating tape spirally wrapped around said pipelines.

3. The maintenance apparatus defined in claim 1 in which the said electric circuit control means for said pump and liquid solution pipeline is a solenoid actuated clutch for said pump and a solenoid actuated valve in said pipeline with wiring therefor to said control center means on said nozzle.

4. The maintenance apparatus defined in claim 3 in which said electric circuit control means for said air pipeline is a solenoid activated valve in said pipeline with

wiring therefor to said control center means on said nozzle.

5. The maintenance apparatus defined in claim 4 in which said control center means on said nozzle is a button actuated electric switch for said electric circuit control for said liquid solution pipeline and a button actuated electric switch for said electric circuit control for said air pipeline.
